UNITED STATES PATENT OFFICE

MICHAEL B. SMITH, OF ST. LOUIS, MISSOURI

DRAIN OPENER

Application filed December 29, 1927. Serial No. 243,258.

My invention relates to improvements in drain openers, and has among its objects the production of a device of such character, which will be neat and compact in construction, simple, economical, convenient, sturdy, and efficient and satisfactory for use wherever found applicable.

One of the objects of my invention is to provide an opener of the kind described, which shall be adapted for insertion through a drain pipe or other similar conduit having any number and direction of bends or angles therealong, said device being equally bendable in all directions, so that it will "take" all of such bends or angles, irrespective of their sharpness or direction.

Another of the objects of my invention is to provide a cleaner of the kind described, which shall be made of flat, flexible wire, twisted loosely to form a spiral of the desired diameter suitable for insertion through the pipe, so that said cleaner may not only be equally flexible in all directions, but will act as an auger to cut away or through sediment or other matter that may have become imbedded in the interior of the pipe and which blocks passage therethrough.

Many other objects and advantages of the construction herein shown and described will be obvious to those skilled in the art to which this invention appertains, from the disclosures herein given.

To this end, my invention consists in the novel construction, arrangement and combination of parts herein shown and described, and more particularly pointed out in the claims.

In the drawings, wherein like reference characters indicate like or corresponding parts throughout the views,

Figure 1 is a sectional view through a portion of the length of a drain pipe installation, showing the cleaning device in position therein;

Figure 2 is an enlarged view of the cleaner;

Figure 3 is a view similar to that shown in Figure 1, but having the additional cutting element; and

Figure 4 is an enlarged fragmentary view,

similar to that shown in Figure 2, and with the auxiliary cutting element in place thereon.

In the drawings, wherein I have illustrated the preferred embodiments of my invention, A indicates a drain pipe or any other conduit, having an obstruction therein at some point along the length thereof (not shown), and which it is desired to clean out or remove therefrom. Such a pipe will most often be made up of a series of pipe lengths or sections, which may be joined together at their abutting ends directly, or through elbows or other special shapes, the various pipe lengths and special section extending at innumerable angles and directions, and lying in various planes relative to one another, and may even have various loops and traps at intervals therealong, (not shown), as it is quite customary to install such elements which have been found necessary for the proper laying or installation of the drain.

When such an installation becomes stopped or blocked at any point, it is a relatively tedious and expensive process to clear the same, as the pipes are either imbedded or hidden behind walls or the like, and on account of the great number and differing directions of the bends. A piece of flexible wire pushed into the pipe will "take" the first bend, as the wire will bend across its width, but if the second bend extends into a plane different from the first section of pipe, the wire will not take the second bend, because of the great resistance of the wire against bending in any direction except across its width, and hence the wire must be pulled out, and the second bend reached by digging.

For these reasons it is necessary to have a cleaner that will "take" all bends and which will have enough rigidity so that it will not twist or curl up and become useless. My improved cleaner comprises one or more sections or lengths, each made up of a piece of flat, relatively stiff and flexible wire, of some suitable material such as steel or the like, the wire being bent or twisted to form an elongated spiral or helix, the pitch of the helix being relatively steep so that a minimum

length of wire will make a maximum length of section, and at the same time retain the special advantages of such construction, to be hereinafter described.

5 Each section B may be removably joined to the adjacent sections by any suitable fastening means such as the screws 2 shown. At the forward end of the forward section inserted through the pipe, there is provided an anti-friction element, such as the ball 3, so that there will be no tendency for the forward tip of the cleaner to become stuck or caught in any of the various joints between the pipe sections through which it must pass. A loop 10 4 may be provided on the cleaner, to receive a rag or the like, for wiping out the interior of a pipe as the cleaner is passed therethrough, and if the loop is provided at the end of the cleaner it may be used for a grip to twist or 15 20 rotate the cleaner during the forward movement through the pipe.

The spirally wound cleaner just described may be passed through any drain or similar conduit, and as the same is made of relatively 25 stiff material, it will not become all twisted up on itself, but will act as a flexible auger to cut its way through any solid matter that may have become accumulated in the pipe sufficiently to obstruct passage therethrough. Such a 30 cleaner will accommodate itself to any and all of the bends or angles in and along the length of the pipe installation, and travel therethrough without the necessity of digging at any point, inasmuch as there is equal 35 ease of bending in all directions laterally of the longitudinal axis of the helix.

When it is desired to clean out pipes having 40 a fairly large bore therethrough, compared to the width of the cleaner element, it may be 45 desirable to have a larger cutter for cutting through larger areas or cross-sections of accumulations, and therefore special cutting members 5 may be detachably secured to the main element B, at some point rearwardly of the ball end of the cleaner. These special cutters 50 are made of a strip of metal much wider than that of which the element is made, twisted to the same pitch so that it may be fitted between adjacent spirals thereof as shown, and may 55 be detachably mounted upon the element B by means of bolts 6 passed through apertures provided in the element B for that purpose.

In order to accommodate various sizes of 55 pipe that may be encountered in practice, there may be a series of these special cutting members 5, of graduated sizes, so that the single main cutting element B may be used with either of the series of special elements 5.

60 Having thus described my invention, it is obvious that various immaterial modifications may be made in the same without departing from the spirit of my invention; hence I do not wish to be understood as limiting myself 65 to the exact construction, form and arrange-

ment of parts herein shown and described, except as limited by the claims.

What I claim as new and desire to secure by Letters Patent is:

1. A cleaner adapted to be inserted through 70 a pipe having a plurality of bends therein and therealong, and comprising a helically-extending flat wire, the diameter of the helix being equal to the width of said flat wire, and the pitch of said helix being relatively steep, 75 whereby said cleaner may be pushed through said pipe from one end thereof and have equal tendencies to bend in all directions of bend.

2. A cleaner of the kind described, comprising a wire twisted along its length to form 80 an elongated auger of a diameter equal to the width of the wire, and a similarly twisted auger element superimposed on said twisted wire and of the same pitch but of greater width than the latter.
